[57] CLAIM

The ornamental design for a razor having a rotatable triangular head, as shown and described.

DESCRIPTION

FIG. 1 is a top and rear perspective view of a razor having a rotatable triangular head, showing my new design; FIG. 2 is a right side view thereof, the unshown opposite side being of mirror-image appearance; FIG. 3 is a rear view thereof; FIG. 4 is a front view thereof; and, FIG. 5 is a top plan view thereof. The undisclosed surfaces are unornamented and follow the contours of the sides shown.
